UNITED STATES PATENT OFFICE.

ELIAS SMITH, OF PEORIA, ILLINOIS, ASSIGNOR OF ONE-HALF TO FRED KIMBLE, OF SAME PLACE.

INDUCTION-COIL.

SPECIFICATION forming part of Letters Patent No. 371,524, dated October 11, 1887.

Application filed July 1, 1887. Serial No. 243,109. (No model.)

To all whom it may concern:

Be it known that I, ELIAS SMITH, a citizen of the United States, residing at Peoria, in the county of Peoria and State of Illinois, have invented certain new and useful Improvements in Electrical Apparatus for Dental Purposes; and I do hereby declare that the following is a full, clear, and exact description of the invention, which will enable others skilled in the art to which it appertains to make and use the same.

This invention relates to an electrical apparatus and its application to dentistry, and has for its object to produce means whereby a current of electricity may be used with advantage to deaden the pain caused by dental operations.

The invention further has for its object to produce means whereby the current readily may be regulated, and whereby, also, the current may be cut off instantly by the operator when desired.

With these objects in view the invention consists in the aggroupments of parts now to be described, and particularly pointed out in the claims.

I have illustrated the invention in the accompanying drawings, in which Figure 1 is a perspective view of the exterior of the case which I employ to hold the batteries, &c., employed in my invention. Fig. 2 is a side elevation of the interior of the case, showing the parts in position, one side of the case being broken away. Fig. 3 is a detail view showing the manner of mounting and adjusting the armature of the induction-coil. Fig. 4 is a view showing the inner face of the board or plate upon which the induction-coil is mounted, illustrating the connections between the induction-coil and the discharges; and Figs. 5 and 6 represent modified forms of tightening devices designed to be applied to the spring carrying the armature of the induction-coil.

For convenience in handling and for the purpose of preventing injury to the cells, &c., employed, the principal portions of the apparatus are confined in a box or case, A, provided at its upper end with a suitable handle,

B. Within this case A is mounted one or more cells, C C, which may be the well-known carbon or any other desirable cell. The elements of these cells are, for convenience in raising them from the jars, connected to a transverse bar, D, which is provided with a vertical rod, E, projecting through the top of the shell or case, so that by raising or lowering the rod the elements are withdrawn from or lowered into the liquid in the jars. The cells are connected to the binding-posts E' F, fixed to a board, G, upon which the induction-coil is mounted. The post F is connected by means of the wire H to the adjustable contact-screw I, against which bears the spring J, and the binding-post E' is suitably connected with the primary of the induction-coil. The purpose of this screw I is, in connection with the spring J, to break and make the primary circuit, and the frequency of the impulses is regulated by the tension of spring J.

The armature K of the induction-coil is mounted at approximately the center of the spring J, so that the vibrations of the armature are varied by the tension of the spring. The spring is mounted in projecting arms L M, projecting from a plate or bar, N, mounted in suitable relation to the induction-coil. One end of the spring is connected permanently to the arm L, and the other end is connected to a lever, O, mounted on the arm M.

The lever O is movable and is manipulated by the screw P, which passes through the lever O and bears against the arm M, so that by turning the screw the lever is moved away from the arm and any desired amount of tension is imposed upon the spring, and thus the rapidity with which the armature vibrates is regulated.

Instead of the means for tightening the spring shown in Fig. 3, I may employ one of the devices shown in Figs. 5 and 6 of the drawings.

In the form of tightener shown in Fig. 5 one end of the spring is permanently connected to the arm L, and the other end is attached to a screw which passes through the arm M, so that by turning the screw back and forth tension may be put upon or taken off the spring.

In the form shown in Fig. 6 the free end of the spring passes through the arm M, and is connected by a pin to an eccentric which bears against the arm, and by which the spring may be tightened in an obvious manner.

The wires from the secondary of the induction-coil are connected, respectively, to the binding-posts Q and R, and the post Q is connected to the post S on the top of the case.

10 The core S' of the induction-coil projects through the shell of the apparatus, as shown, for convenience in manipulating it.

The post R is connected with a spring, U, fixed, preferably, at about the bottom of the case. One end of this spring is fixed permanently, and the free end bears, when in its normal position, against a metal plate, V. To the outside of the case is pivoted a lever, W, provided with a knob or projection which projects through an opening in the side of the case and bears against the spring U near its free end. This lever is of such a length that when the box or case rests upon the floor it may be pressed by the foot of the operator, whether he be standing on the floor or on a stool. Pressure on the lever W will separate the spring U and metal plate, and thus break the circuit. The plate V is connected to a post, T, fixed to the outside of the box or case.

15 30 The cylinders or electrodes, designed to be held in the hands of the person to be operated upon are connected, respectively, to the binding-posts T and S. The post T is connected with a binding-post, Y, by means of a wire, Z, and to this post is connected a pair of forceps or other instruments to be used in operating upon the patient.

In using the apparatus the electrodes are grasped by the patient and the elements of the batteries are lowered into the jars, thereby generating a current of electricity which passes through the circuit completed by the person holding the electrodes. When the forceps which are connected, as described, with the post Y are brought into contact with the tooth, a circuit through the forceps and tooth is completed, thus causing a portion of the current formerly passing through the hands holding the electrodes connected to the post to pass through the tooth, and thus the desired numbing effect is produced. After the operation the lever W is pressed in by the foot of the operator or otherwise and the circuit broken.

20 25 35 40 45 50 55 Having thus described my invention, what I claim as new, and desire to secure by Letters Patent, is—

1. In an electrical apparatus for dental purposes, a generator, an induction-coil having its armature mounted on a spring supported at both ends, and electrodes, substantially as described.

2. In an electrical dental apparatus, a generator, an induction-coil having its armature mounted on a spring fixed at one end and provided at the other with a tension device, whereby the rapidity of the electrical impulses allowed to pass through the induction-coil is regulated, and the electrodes, substantially as described.

3. In an electrical apparatus for dental purposes, the generator, the induction-coil having its armature mounted on a spring fast at one end and secured at the other to a lever and set-screw, whereby the rapidity of the electrical impulses allowed to pass through the induction-coil is regulated, and the electrodes, substantially as described.

4. In an electrical apparatus for dental purposes, a generator, an induction-coil, the electrodes, and the wire from one of the discharge-posts connected with a pair of forceps or the like, substantially as described.

5. In an electrical apparatus for dental purposes, the elongated spring U, forming a portion of the circuit, and the elongated lever W, mounted on the exterior of the case, and having a projection extending through the case and bearing against the spring, substantially as described.

6. The combination, in an electrical apparatus for dental purposes, of one or more battery-cells, an induction-coil having its armature mounted on a spring supported at both ends and provided with a tension device, the electrodes, and the forceps or other instrument attached to one of the electrodes, substantially as described.

7. The combination, in an electrical apparatus, of one or more cells, an induction-coil having its armature mounted on a spring supported at both ends and provided with a tension device, the elongated spring forming part of the circuit, the lever mounted on the case and bearing against the spring, the electrodes, and the forceps or the like connected with one of the electrodes, substantially as described.

In testimony whereof I affix my signature in presence of two witnesses.

ELIAS SMITH.
